DESIGN FOR A WALL BRACKET LAMP

Edward Kanter, Cleveland Heights, Ohio, assignor to Railley Corporation, a corporation of Ohio

Application October 21, 1936, Serial No. 65,401

Term of patent 7 years

To all whom it may concern:

Be it known that I, Edward Kanter, a citizen of the United States, residing at Cleveland Heights, in the county of Cuyahoga and State of Ohio, have invented a new, original, and ornamental Design for a Wall Bracket Lamp, of which the following is a specification, reference being had to the accompanying drawing, forming part thereof, wherein the single figure is a perspective view of a wall bracket lamp embodying my new design.

The opposite side of the support member which is not disclosed in the drawing is substantially the same in appearance as the side disclosed.

I claim:

The ornamental design for a wall bracket lamp substantially as shown and described.

EDWARD KANTER.
